WRINGER HEAD

Julian L. Perkins, West Springfield, Mass.

Application May 18, 1936, Serial No. 80,238

3 Claims. (Cl. 74—337.5)

This invention relates to improvements in wringer heads and is directed more particularly to a unitary wringer head including a housing including mechanism for driving a wringer.

5 The principal objects of the invention are directed to the provision of a wringer head which is simple in form and efficient in its operation.

A further object of the invention is the provision of a wringer head wherein a driving element or elements are shifted into and out of engagement with the driving element as by being reciprocated in one direction or the other by a swinging operating member, there being novel means for transforming the swinging motion 15 of the operating member so that it reciprocates the driven element.

Various novel features and advantages of the invention will be hereinafter more fully referred to in connection with the accompanying description 20 of the present preferred form of the invention, reference being had to the drawing wherein:

Fig. 1 is a partial side elevational and sectional view showing a wringer head embodying the novel features of the invention;

25 Fig. 2 is a sectional plan view on the line 2—2 of Fig. 1;

Fig. 3 is a fragmentary plan view of the casting of the wringer head to explain certain novel features of the invention; and

30 Fig. 4 is a side elevational view of the operating member constituting a part of the invention.

Referring now to the drawing in detail the invention will be more fully described.

The wringer head of the invention consists 35 of a casing indicated generally by 2 which functions as a support and which has intersecting horizontal and vertical bores 4 and 6.

A vertical part 8 of the casing in which the bore 6 is located is adapted for resting on a column of a washing machine and it may be rotatable with respect thereto. 10 represents a drive shaft such as is usually associated with a washing machine and on its upper end there is a driving element in the form of a pinion 12.

45 Upper and lower ears 14 are provided which have openings 16 therethrough. To these a wringer may be secured.

A pair of driven elements such as gears 18 are 50 fixed to a shaft 20 by means of pins such as 22 and these gears are slideable and rotatable in the bore 4. An inner end 24 of the shaft 20 is adapted for coupling to the driving shaft of a wringer. A shifting member in the form of a collar 26 is carried by said shaft 20 and is rotatable relative thereto.

The gears 18 and collar 26 in Fig. 1 are shown in a neutral inoperative position and are shiftable longitudinally along the bore so that either one of the gears 18 may be engaged with the pinion 12. According to the direction of rotation of the pinion 12, the shaft 20 is rotated in one direction or the other accordingly as one or the other of the pinions is brought into mesh with the gear 12.

The gears 18 are preferably of the type known 10 as face-gears which have teeth extending inwardly on their adjacent faces. An operating member 28 has a leg part 30 which is pivoted as by a screw 32 to the rear end 34 of the housing so that it may swing on a horizontal axis back 15 and forth from the neutral inoperative position shown in Fig. 1 to an operative position at either side thereof. A shroud part 26' of the operating member 28 overlies the upper side of the housing and a curving manually engageable part 38 extends 20 forwardly and upwardly from the part 30. This member 28 is arranged to have an opening 49 therethrough so that an operator may grasp the part 38 to swing the operating member on its pivot.

A rib or ribs such as 42 on the outside of the housing at the inner or right hand end thereof is arranged so that the forward end of the operating member rests and slides thereon. To cover up this rib there are on either side of the operating member, downwardly depending skirt portions 42'. The forward end of the operating member 28 bears on the rib so that it may slide thereon as it is swung between operative and inoperative positions.

35 A slot 50 is provided in the upper side of the housing which is disposed beneath the operating member as shown in Figs. 2 and 3. This slot provides a cam surface or surfaces for a pin 52 carried by member 26 which extends through 40 the slot 50. As the pin 52 is moved along the slot in one direction or the other the collar or shifting member 26 and the gears 18 are shifted longitudinally.

A member 54 is pivoted at 56 to the operating 45 member 28 and a detent 58 associated therewith extends through an opening 60 in the said member. This is arranged to enter a socket 62 in the upper side of the casing. When the lever member 28 is in the neutral position shown in 50 Fig. 1, the detent is received in the socket 62.

To release the operating member for its swinging movements to shift the gears the part 38 of the operating member and lever 54 are 55 squeezed between the fingers so that the detent

is withdrawn from its socket. A spring 64 secured at one end to the member 28 bears on the lever 54 and tends to urge the member downwardly so the detent will pass into the socket 5 when the operating member is moved from an operating position to its inoperative neutral position.

The underside of the shroud 36 of the operating member is provided with a slot 66 which 10 preferably extends in a direction opposite to that of the slot 50 of the housing (see Figs. 2 and 3). At either end of the slot 66 there are sockets 68 having angularly disposed sides.

As shown in Fig. 2, the operating member 38 15 is in a neutral inoperative position, the pin 52 being in the center of the slot 50. To shift pin 52 to bring one of the gears into engagement with the pinion, the pin 52 is moved along slot 50. This is accomplished by swinging the operating member in one direction or the other.

For instance, in Fig. 3 the parts forming the slot 66 and socket 68 of the operating member are shifted so as to move the pin 52 in such a direction as to move the gears 18 in Fig. 1 to 25 the left. When the operating member has been tilted sufficiently to move the pin 52 so that the right hand gear is in mesh with the pinion, the said pin is in the socket of the operating member at the end of the slot 66.

30 The form of the socket will be clear from Fig. 3 and is such that the pin is releasably held against accidental movements along the slot because it is received in a socket of the operating member. When however it is desired to re- 35 turn the mechanism to an inoperative neutral position, the operating member is swung toward the center or upwardly in Fig. 3 thereupon the side 67 of the slot brings up against the pin 52 to force it along slot 50 and through the slot 40 68. When the operating member has reached its inoperative neutral position, the pin in the position shown in Fig. 2 with reference to the slot and the detent enters the socket 62.

While I have described the invention in great 45 detail and with respect to a preferred form thereof, it is not desired to be limited thereto since many changes and modifications may be made therein without departing from the spirit and scope of the invention. What it is desired to 50 claim and secure by Letters Patent of the United States is:

1. A head for a wringer or the like comprising

in combination, a housing, engageable driving and driven members therein, a shifter for said members movable in the housing, a swinging operating member pivoted at one end to said housing and having a forwardly extending part 5 overlying said housing, the housing being provided with a cam surface, the said forwardly extending part provided with a cam surface, a part associated with said shifter disposed to be acted upon by said cam surfaces, all adapted and arranged whereby the swinging of the operating member brings about movements of said shifter, and locking means carried by said operating member to releasably lock the member against movement.

2. A head for a wringer or the like comprising in combination, a housing, engageable driving and driven members therein, a shifter for said members movable in the housing, a swinging operating member pivoted at one end to said 10 housing and having a forwardly extending part overlying said housing, the housing being provided with a cam surface part, the said forwardly extending part provided with a cam surface, a part associated with said shifter disposed to be acted upon by said cam surfaces, all adapted and arranged whereby the swinging of the operating member brings about movements of said shifter, the operating member being provided with an opening therethrough and a hand grip, 20 and a lock member associated therewith which is disposed to be gripped simultaneously with the said hand grip.

3. A head for a wringer or the like comprising in combination, a housing, engageable driving and driven members therein, a shifter for said members movable in the housing, a swinging operating member pivoted at one end to said 25 housing and having a forwardly extending part overlying said housing, the housing being provided with a cam surface, the said forwardly extending part provided with a cam surface, a part associated with said shifter disposed to be acted upon by said cam surfaces, all adapted and arranged whereby the swinging of the operating member brings about movements of said shifter, and locking means carried by said operating member to releasably lock the member against movement including means to urge the locking means into locking position.

50 JULIAN L. PERKINS.
